UNITED STATES PATENT OFFICE.

ADDISON C. SMITH, OF ALGONA, IOWA.

WASH-BOILER.

SPECIFICATION forming part of Letters Patent No. 440,660, dated November 18, 1890.

Application filed January 14, 1890. Serial No. 336,955. (No model.)

To all whom it may concern:

Be it known that I, ADDISON C. SMITH, a citizen of the United States of America, and a resident of Algona, in the county of Kos-
5 suth and State of Iowa, have invented a Clothes-Drainer Attachment for Wash-Boilers, of which the following is a specification.

My object is to avoid the annoyances, dangers, and accidents incident to taking cloth-
10 ing out of hot soapsuds in a boiler; and my invention consists in the construction and combination of a drainer with the top of a boiler, as hereinafter set forth, pointed out in my claims, and illustrated in the accom-
15 panying drawings, in which—

Figure 1 is a top view; Fig. 2, a transverse vertical sectional view; and Fig. 3 a perspective view showing the drainer applied to a boiler as required for practical use. Fig.
20 4 shows a modified form of the drainer.

A represents a vessel or wash-boiler adapted for boiling clothing therein. It is preferably of oblong form, as shown, but may be square-cornered and vary in size, as desired.

25 B is an open-topped sheet-metal drainer adapted to be connected with the top edge of a boiler. It has hand-holes at its ends and a water-tight bottom. Immediately above the bottom the vertical part or wall is open
30 to allow water to flow from the drainer and over the bottom, to be thereby directed into the boiler. The opening may be several inches wide and extend the entire length of the flange, and have wire or strips of sheet
35 metal fixed across in vertical or horizontal positions, as required, to prevent small articles or parts of clothing from slipping into or through the opening; or the wall may be perforated or slotted to allow water to drain
40 through and pass over the bottom into the boiler.

C represents a bracket, preferably made of tin straps, malleable iron, or non-corrosive wire, and adapted in form to hang upon the
45 top edge of the boiler and to support the drainer. It has a duplex hook, one part of said hook projecting forward and downward to overlap the top edge of the boiler, and the other part projecting horizontally to overlap
50 the edge of the bottom of the drainer.

To attach the drainer to the boiler, I hang

two brackets on the boiler, and then place the drainer on top of the brackets in such a manner that it will incline sufficiently to allow water in the drainer to flow into the 55 boiler, and when the drainer is thus applied and clothing is to be taken from the hot wa-
ter or soapsuds in the boiler I lift the arti-
cles successively with a stick, hook, or other
suitable device and place them in the drainer. 60 Dripping hot water outside of the boiler will be thus prevented, and the clothes will be drained and cooled before they need to be touched with the hands, and before separating them by hand they can be conveniently car-
ried in the drainer to any place desired. 65 Wetting floors and scalding hands will not occur, and the labor of taking out and drain-
ing and carrying about articles subjected to a boiling process will be greatly facilitated 70 by the use of my invention.

To economize space in packing and ship-
ping, my drainer attachment may conform
in size and shape with a boiler, so that it can
be placed in the boiler when not in use. 75

I am aware that a dish-pan drainer having an open side and its bottom extended and bent downward at the open side and fixed legs to support it has been detachably connected with a dish-pan in such a manner that water 80 in the drainer would descend therefrom into the pan; but my manner of making a flat-
bottomed drainer adapted to be placed inside of a boiler to rest upon its flat bottom, or to be placed upon the flat top of a table or other 85 even surface, and also adapted to be com-
bined with a wash-boiler by means of de-
tachable brackets in such a manner that the
edge of its bottom at its open side will pro-
ject inward over the top edge of the boiler, 90
is novel and greatly advantageous.

I claim as my invention—

1. An open-topped flat-bottomed drainer-
vessel having openings in one side to admit
projections on brackets and to discharge wa-
ter, and adapted in size and shape to be
placed in a wash-boiler of common form, and
brackets adapted to hang on the edge of an
open-topped wash-boiler and provided with
projections to enter the open side of the 100
drainer and to support the drainer in an in-
clined position, in combination with a wash-

boiler, substantially as shown and described, for the purposes stated.

2. An elbow-shaped bracket having a duplex hook at its corner, one part of said hook extending inward and downward to engage the top edge of a wash-boiler, and the other

tally to engage the bottom edge of a drainer, in combination with a wash-boiler and a drainer, for the purposes stated.

ADDISON C. SMITH.
